(57) CLAIM

The ornamental design for a garment, as shown and described.

DESCRIPTION

FIG. 1 is a front perspective view of a garment showing our new design.

FIG. 2 is a front view of the garment.

FIG. 3 is a rear view of the garment.

FIG. 4 is a left-side view of the garment.

FIG. 5 is a right-side view of the garment.

FIG. 6 is a top view of the garment.

FIG. 7 is a bottom view of the garment; and,

FIG. 8 is a front perspective view of the garment when in use. The short broken lines showing elements of the garment in the drawings illustrate features of the article of manufacture that form no part of the claimed design. The human figure rendered in short broken lines in FIG. 8 illustrates environmental subject matter intended to assist in showing how the design appears when in use and forms no part of the claim.
